ATTORNEYS.

UNITED STATES PATENT OFFICE.

ROBERT M. STEINDLER, OF NEW YORK, N. Y.

DESIGN FOR A SKIRT-HOLDER.

SPECIFICATION forming part of Design No. 27,586, dated August 31, 1897.

Application filed April 24, 1897. Serial No. 633,802. Term of patent 7 years.

To all whom it may concern:

Be it known that I, ROBERT M. STEINDLER, of New York city, county and State of New York, have invented and produced a new and original Design for an Elastic Bicycle-Skirt Holder, of which the following is a full, clear, and exact description.

Reference is to be had to the accompanying drawing, the figure shown being a perspective view of an elastic bicycle-skirt holder, showing my design.

The leading feature of my design consists in the L-shaped configuration given to the holder by forming the leg or garter band near its

buckle end with a member B in the form of a short band and which extends approximately at right angles from and in a plane with the flat face of the band A, as is plainly shown in the drawing. The outer end of the member B is ornamented with a fastening C.

I claim—

The design for an elastic bicycle-skirt holder as herein shown and described.

ROBERT M. STEINDLER.
